(57) **CLAIM**

We claim the ornamental design for a valve, as shown and
described.

DESCRIPTION

FIG. 1 is a bottom left perspective view of a first embodiment
of a valve showing our new design;

FIG. 2 is a front elevation view of the valve shown in FIG.
1, with the valve being illustrated in the closed position;
FIG. 3 is a rear elevation view of the valve shown in FIG.
1;

FIG. 4 is a left side elevation view of the valve shown in
FIG. 1;

FIG. 5 is a right side elevation view of the valve shown in
FIG. 1;

FIG. 6 is a top plan view of the valve shown in FIG. 1;

FIG. 7 is a bottom plan view of the valve shown in FIG. 1;
FIG. 8 is another front elevation view of FIG. 1, with the
valve being illustrated in the open position;

FIG. 9 is a bottom left perspective view of a second
embodiment of a valve showing our new design.

FIG. 10 is a front elevation view of the valve shown in FIG.
9, with the valve being illustrated in the closed position;
FIG. 11 is a rear elevation view of the valve shown in FIG.
9;

FIG. 12 is a left side elevation view of the valve shown in
FIG. 9;

FIG. 13 is a right side elevation view of the valve shown in
FIG. 9;

FIG. 14 is a top plan view of the valve shown in FIG. 9;
FIG. 15 is a bottom plan view of the valve shown in FIG. 9;
and,

FIG. 16 is the same front view of the valve as shown in FIG.
10, with the valve being illustrated in the open position.
The broken lines shown in the figures are included for the
purpose of illustrating portions of the valve which form no
part of the claimed design.
